UNITED STATES PATENT OFFICE.

JOHN DICKSON, OF VANCOUVER, WASHINGTON.

PULVERIZED-FUEL-BURNING DEVICE.

1,349,148.

Specification of Letters Patent. Patented Aug. 10, 1920.

Application filed July 23, 1917. Serial No. 183,341.

To all whom it may concern:

Be it known that I, JOHN DICKSON, a citizen of the United States, and a resident of Vancouver, in the county of Clarke and State of Washington, have invented a certain new and useful Improvement in Pulverized-Fuel-Burning Devices, of which the following is a specification.

My invention relates to improvements in devices for burning pulverized fuel, and more especially to devices for enabling locomotive engines to make use of pulverized fuel, and it consists in the combinations, constructions, and arrangements herein described and claimed.

An object of my invention is to provide a device by means of which pulverized fuel may be so introduced into the combustion chamber of a locomotive or other fuel burning apparatus that the fuel is substantially consumed, leaving a relatively small amount of ash and giving a maximum quantity of heat.

A further object of my invention is to provide a device of the type described in which the fuel is conveyed from the tender to the locomotive fire box by means of a stream of heated air, the air aiding in effecting complete combustion.

A further object of my invention is to provide a novel form of burner device in which the burner is introduced at the front end of the fire box and a flame is projected to the rear end of the same.

A further object of my invention is to provide an expansion air tank which is located in the smoke box of the locomotive, thus utilizing the exhaust gases to heat the air supply.

Other objects and advantages will appear in the following specification and the novel features of the invention will be particularly pointed out in the appended claims.

My invention is illustrated in the accompanying drawings forming a part of this application, and in which:

Figure 1 is a general plan view of the apparatus;

Fig. 2 is a side view of the general arrangement, certain parts being shown in section and other parts being omitted for the sake of clearness;

Fig. 3 is a sectional view of a conveyer and a portion of the blower system;

Fig. 4 is a plan view of the parts shown in Fig. 3;

Fig. 5 is a sectional view showing the arrangement of the burner, and

Fig. 6 is a detail view of a portion of certain air pipes, showing their manner of connection.

In carrying out my invention I may make use of a locomotive engine, such as shown at A in Fig. 2, and the tender B. At 1 I have indicated in general the fire box 65 or combustion chamber of the locomotive. This consists of a chamber which is preferably lined with heat resisting material, having at the rear end an opening 2 for the admission of air. Disposed at the front of the 70 fire box is a burner nozzle 3 which is connected with a pipe 4 bent downwardly and rearwardly and extending toward the tender. This pipe is provided with a flexible hose connection 5 and a discharge nozzle 6, 75 from which the pipe 4 receives fuel.

The pulverized fuel is carried in a hopper 7 on the tender. This hopper consists of a casing having a sloping bottom 8 leading toward a conveyer casing 9, the latter 80 housing a screw conveyer 10.

The shaft 19 of this screw conveyer extends to a motor M, which is driven by steam admitted through a steam pipe 20 by means of a valve 21, a flexible hose connection being used between the tender and the engine in the pipe 20. One end of the conveyer casing 9 communicates with the discharge nozzle 6 by means of an inclined pipe 22.

Disposed at 23 in the smoke box 24 of the locomotive is a tank having a pipe 25 extending rearwardly and connecting with the nozzle 6 at 25^x, see Figs. 3 and 4. The opposite side of the tank 23 is provided with a pipe 26 which communicates with an air tank 27 on the tender. A pipe 28 leads from the air tank 27 to the air pump 29 on the engine. The pipe 25, it will be observed, has a series of pipes 30 connecting the pipe 25 with the pipe 4, these pipes 30 being inclined in such manner as to facilitate the flow of air through the pipe 4 in the manner hereinafter explained.

From the foregoing description of the 105 various parts of the device, the operation thereof may be readily understood.

The hopper 7 is filled with pulverized fuel, such as pulverized coal. The fuel tends to move toward the conveyer casing 9. 110 This casing has an opening 9^x at its top, see Figs. 1 and 4, for permitting the fuel to

enter into the casing. By manipulating the valve 21, see Fig. 2, steam may be admitted through the pipe 20 to the motor M, and the conveyor 10 is thereby operated, and the 5 coal is caused to pass forwardly down through the pipe 22 and into the discharge nozzle 6.

In the meantime the air pump 29 is supplying the tank 27 with compressed air, this 10 air passing through the pipe 28. The air passes from the tank 27 through the pipe 26 to the tank 23, where the air is heated and caused to expand and it returns from the tank 23 by the pipe 25 which connects 15 with the nozzle 6, as hereinafter explained, this air being under relatively low pressure. The pressure is sufficient, however, to carry the coal forwardly, the carrying action being boosted or assisted by streams of warm 20 air directed through pipes 30. The mixture of warm air and pulverized fuel is ignited by placing a piece of burning waste to the mouth of the burner nozzle 3.

The exhaust of the cylinders creates a vacuum in the smoke box of the locomotive, 25 and this forces the hot gases and products of combustion from the fire box through the flue into the smoke box, thus heating the air in the tank 23. The pipe 26 which 30 delivers air from the air tank 27 to the expansion tank 23 is controlled by means of a valve 31 on the engine.

While I have shown the device as being applied to a locomotive engine, it will be 35 understood that it may be used on any furnace having exhaust gases which could be utilized to heat an expansion air tank.

I claim:

1. A device for feeding pulverized fuel 40 comprising a tender having a fuel hopper, a locomotive engine having a fire box, a burner nozzle disposed at the front of the fire box and directed toward the rear, a fuel

pipe connected with said burner nozzle and 45 extending rearwardly toward the tender, a nozzle discharging into said pipe and carried by the tender, means for introducing compressed air into said discharge nozzle, 50 connections between said discharge nozzle and said fuel hopper for introducing fuel into said discharge nozzle whereby the fuel 55 is delivered to the burner nozzle, auxiliary air pipes connected with said fuel pipe, said air pipes being directed to assist in the travel of the fuel, means for heating the air prior to its delivery to said discharge nozzle and to said fuel pipe, said last named means comprising a tank disposed in the smoke box of the locomotive, and means for forcing air through said tank. 60

2. A device for feeding pulverized fuel, comprising a tender having a fuel hopper, a locomotive engine having a fire box, a burner nozzle disposed at the front of the fire box and directed toward the rear, a fuel 65 pipe connected with said burner nozzle and extending rearwardly toward the tender, a nozzle discharging into said pipe and carried by the tender, means for introducing compressed air into said discharge nozzle, 70 connections between said discharge nozzle and said fuel hopper for introducing fuel into said discharge nozzle whereby the fuel is delivered to the burner nozzle, auxiliary air pipes connected with said fuel pipe for 75 assisting the travel of the fuel, means for heating the air prior to its delivery to said discharge nozzle, said last named means comprising a tank disposed in the smoke box of the locomotive, and an air pump carried by the locomotive and communicating 80 with said tank. 75
